UNITED STATES PATENT OFFICE.

CHARLES A. TATUM, OF NEW YORK, N. Y., ASSIGNOR TO WHITALL TATUM CO., OF NEW YORK, N. Y., A CORPORATION OF NEW JERSEY.

DESIGN FOR A FOUNTAIN-SYRINGE BAG.

42,809.

Specification for Design.

Patented July 16, 1912.

Application filed April 12, 1912. Serial No. 690,369. Term of patent 14 years.

To all whom it may concern:

Be it known that I, CHARLES A. TATUM, a citizen of the United States, and resident of the borough of Manhattan, city, county, and State of New York, have invented a new, original, and ornamental Design for Fountain-Syringe Bags, of which the following is a specification.

Reference is to be had to the accompanying drawing which illustrates a face view

of a fountain syringe bag showing my new design.

I claim:

The ornamental design for a fountain syringe bag as shown.

CHARLES A. TATUM.

Witnesses:
